UNITED STATES PATENT OFFICE.

FRANCIS H. SMITH, OF WASHINGTON, DISTRICT OF COLUMBIA.

DESIGN FOR A GUMMED STAMP.

SPECIFICATION forming part of Design No. 21,140, dated October 27, 1891.

Application filed September 24, 1891. Serial No. 406,746. Term of patent 7 years.

To all whom it may concern:

Be it known that I, FRANCIS H. SMITH, a citizen of the United States, residing at Washington, in the District of Columbia, have invented and produced a new and original Design for Gummed Stamps, of which the following is a specification, reference being had to the accompanying drawing, forming part thereof.

10 The drawing illustrates my design for a gummed stamp.

The leading feature of my design consists in a shield having a peculiarly-arranged surface located in a field having an escaloed 15 edge.

A represents the field on which my design is located, having an escaloed edge B. Upon the field A is represented a shield C, having its upper portion D formed with inclined sides E, with convolutions F at its corners, and a central tapering portion G. At

the base of the upper portion D is shown a narrow encircling band H. The central portion of the shield C appears as a plain ground or field I. Beneath the field I the face of the 25 shield C is shown as having a net-work K, separated from the field I by an undulating line J. The lower portion of the net-work K presents a blank strip L, having a curved upper edge M and a lower tapering central portion N conforming to the bottom tapering portion O of the shield C.

Having described my invention, what I claim is—

The design for gummed stamps, as herein 35 shown and described.

In testimony whereof I have affixed my signature in presence of two witnesses.

FRANCIS H. SMITH.
